UNITED STATES PATENT OFFICE.

WILLIAM C. HOMAN, OF MERIDEN, CONNECTICUT, ASSIGNOR TO THE
EDWARD MILLER & COMPANY, OF SAME PLACE.

SHADE-HOLDER.

SPECIFICATION forming part of Letters Patent No. 536,207, dated March 26, 1895.

Application filed December 28, 1894. Serial No. 533,201. (No model.)

To all whom it may concern:

Be it known that I, WILLIAM C. HOMAN, a citizen of the United States, residing at Meriden, New Haven county, Connecticut, have 5 invented a new and useful Improvement in Shade-Holders, of which the following is a specification.

My invention relates to that class of shade holders in which a plurality of radial arms is 10 pivotally connected with a ring adapted to embrace a portion of the lamp burner. It is intended to produce a very cheap and efficient holder, easily packed for shipment.

In the accompanying drawings Figure 1 15 represents in perspective so much of a lamp as is necessary to show my invention with my shade holder attached thereto, and partly broken away. Fig. 2 shows my shade holder detached from the lamp. Fig. 3 is a portion 20 of my device modified in form.

The same letters refer to like parts in the several views.

A designates a lamp; a, a cylindric band on said lamp; B, a shade holder band portion; 25 b, an ear on the portion B; C, a shade holder arm provided with eye c, heel c' and hook c'', and in Fig. 3, with brace c'; D, a rivet.

In the example of my invention illustrated in Figs. 1 and 2 of the drawings the lamp A 30 may be of any desired configuration and the cylindric band or collar a may be at any convenient point above the fount of the lamp, as desired. The shade holder band consists of a plurality of arc shaped portions B, here 35 shown as three in number, each of which is provided at each end with an outturned ear b. Each of the arm portions C, preferably made of wire as shown, is provided with an eye c at its inner end, a bend or heel c' a short 40 distance from said eye, a straight or slightly curved body and a hook c'' at its outer end. The eye c of the arm C is pivotally secured between the ears b of the band portions by means of a rivet D passing through the ear b and the eye. The completed shade holder is shown in Fig. 2. It will be seen that it may be folded in small compass for shipment. This is of great advantage in that it permits 45 the shade holder to be packed in a box with 50 the lamp.

In Fig. 1 is shown my device in operation. It will be seen that the band fits around the cylindric portion a of the lamp A in the usual

manner. The arms C are pressed radially outward and downward until the heel c' strikes 55 the lamp A below the portion a. The shade may be placed on the holder the hooks c'' being adapted to receive and support its lower edge as indicated by a dotted line in Fig. 1.

In Fig. 3 I have shown a modified form of 60 the arm C. It differs from that above described in having a brace c' extending from the heel c' outward and secured at its outer end to the arm near the hook c''. I prefer to make the arm C including the brace c' of a 65 single piece of wire as shown.

I am aware that shade holders have heretofore been made in which radial arms were pivoted to a band. I do not of course wish to be understood as claiming such a device 70 except in the combination above set forth.

What I claim as my invention, and desire to secure by Letters Patent of the United States, is as follows:

1. In a shade holder in combination a plurality of arc shaped band sections and a plurality of radial arms pivotally secured at the adjacent ends of said band sections, substantially as described. 75

2. In a shade holder in combination a plurality of arc shaped band sections each of which is provided with a radially projecting ear at each end and a plurality of radial arms pivotally secured between said ears, substantially as described. 80

3. In a shade holder in combination a plurality of arc shaped band sections and a plurality of radial arms pivotally secured at the adjacent ends of said band sections, each of said arms consisting of an eye, a bend forming a heel below said eye, a body portion and a hook adapted to receive a shade, substantially as described. 90

4. In a shade holder in combination a plurality of arc shaped band sections and a plurality of radial arms pivotally secured at the adjacent ends of said band sections, each of said arms consisting of an eye, a bend forming a heel below said eye, a body portion, a brace extending from said heel to said body 95 and a hook adapted to receive a shade, substantially as described.

WILLIAM C. HOMAN.
